WILLIAM GARRISON, OF CLARKSTOWN, NEW YORK.

Letters Patent No. 100,747, dated March 15, 1870.

IMPROVEMENT IN MECHANICAL MOVEMENTS.

The Schedule referred to in these Letters Patent and making part of the same

To all whom it may concern:

Be it known that I, WILLIAM GARRISON, of Clarkstown, in the county of Rockland, and State of New York, have invented a new and improved Mechanical Movement; and I do hereby declare that the following is a full, clear, and exact description thereof, which will enable others skilled in the art to make and use the same, reference being had to the accompanying drawings forming part of this specification.

Figure 1 represents a vertical transverse section of my improved mechanical movement.

Figure 2 is a side view, partly in section, of the same.

Figure 3 is a plan or top view of the same.

Figure 4 is a detail side view of the same, showing its parts out of gear.

Similar letters of reference indicate corresponding parts.

This invention relates to a new mechanism for converting oscillating into rotary motion, and is chiefly applicable to machines for elevating or conveying heavy loads by means of ropes or chains wound upon or unwound from rotating drums.

The invention consists in such a combination of a pivoted lever with double pawls and two rotating geared drums that at every oscillation of the lever the drums are both rotated in opposite directions, the motion of each drum being continuous as long as that of the lever is carried on.

The invention consists, also, in so pivoting the lever that the same can, with both pawls, be readily thrown out of gear.

A, in the drawing, represents a frame, which supports two parallel arms or shafts, B C, that are geared together by means of toothed wheels *a b*, mounted upon them respectively. The drums are thus so connected that when one is turned the other will revolve in an opposite direction.

To the frame is secured, equidistant from the axes of the two drums and parallel with the same, a pin, *c*, which serves as a pivot for a lever, D.

To the lever D are pivoted, by separate pins *d e*, two pawls, E and F, which project respectively toward the two drums, catching with their points into the teeth of ratchet-wheels *f g*, that are respectively mounted upon the said drums, and whose teeth are in opposite directions, as shown.

It is evident that as the lever is rocked on its pivot it will carry the pawls alternately against the two ratchet-wheels and apply motion in opposite directions to the two drums. But as by the gearing together of the drums their motion is already made to be opposite, the regular motion of each is merely kept up by the alternate action of the two pawls. Thus the oscillation of the lever serves to revolve continuously two drums, the revolution of each serving during half the time to produce that of the other, and *vice versa*.

The aperture of the lever D, where the same embraces the pin *c*, is enlarged at one end, as shown in fig. 2, so that the lever can be leaned obliquely, as in fig. 4. When thus inclined, the lever holds the pawls out of gear and allows the ropes or chains on the two drums to unwind.

A brake, G, may be arranged on one or both the said drums for regulating the unwinding motion.

Having thus described my invention,

I claim as new, and desire to secure by Letters Patent—

1. The combination of the lever D and pawls E F with the drums B C, toothed wheels *a b*, and ratchet-wheels *f g*, all parts being arranged so that the oscillation of the lever will produce continuous rotation of both drums in opposite directions, as set forth.

2. The lever D, which carries the pawls for rotating the drums B C, when so pivoted that it can be inclined to carry both pawls out of gear, as specified.

WILLIAM GARRISON.
